C. L. Rehn & H. Everett: Design for Metal Cage.
Fig. 5. Patented Oct. 13, 1891.

No. 952.

Fig. 4.

Fig. 2.

UNITED STATES PATENT OFFICE.

C. L. REHN AND H. EVERETT, OF PHILADELPHIA, PENNSYLVANIA.

DESIGN FOR METAL KEGS.

Specification forming part of Design No. 952, dated October 13, 1857.

To all whom it may concern:

Be it known that we, C. L. REHN and H. EVERETT, of Philadelphia, in the county of Philadelphia and State of Pennsylvania, have invented a new and original ornamental Design for Metal Kegs; and we do hereby declare that the following is a full, clear, and exact description of the same, reference being had to the accompanying drawings, forming part of this specification, in which—

Figure 1 is a side elevation, Fig. 2 a profile section, and Fig. 3 a plan or end view, of a metal keg formed and configured according to our design.

Similar letters of reference in each of the several figures indicate corresponding parts.

The nature of our invention consists in the combination of the curved hoops in relief on a foundation forming a regular bulge with the beading and ornamental configuration of the top of the keg in the manner shown in the drawings, the whole forming a new ornamental design for a metal keg.

In producing our design we take zinc or other metal which can be spun into the desired form and spin out the keg in two equal sections A B in such form that when united together the keg will have the bulge usually given to wooden kegs and barrels. At the same time that the process of spinning the sections A B is performed raised horizontal ribs C C are produced in relief, so as to rep-

resent hoops, said ribs being curved at b b, so as to give an ornamental finish to the keg. On the lower section the bottom is spun so as to form part of it, a raised bead being formed at d, said bead terminating in a depressed curved ornamental form e. The upper section terminates in a curved groove f, the top or cover being separate from it and having a curved ornamental tongue formed at h and a bead i and depressed to a curved ornamental form at j. The top or cover also is ornamented at its center by raised ornaments of the character shown in Fig. 3 and designated by the letters k l m n, said ornaments being produced by the ordinary stamping process.

What we claim as our invention, and desire to secure by Letters Patent, is—

The combination of the curved hoops in relief on a foundation forming a regular bulge with the beading and ornamental configuration of the bottom or top of the keg in the manner described and shown in the drawings, the whole forming a new ornamental design for a metal keg.

The above specification of our ornamental design for metal kegs signed by us and witnessed this 22d day of September, 1857.

C. L. REHN.
H. EVERETT.
